UNITED STATES PATENT OFFICE.

WARD W. YOUNG, OF PAULDING, OHIO.

SLEEVE OR CUFF BUTTON.

SPECIFICATION forming part of Letters Patent No. 274,245, dated March 20, 1883.

Application filed August 8, 1882. (No model.)

To all whom it may concern:

Be it known that I, WARD W. YOUNG, a citizen of the United States of America, residing at Paulding, in the county of Paulding and State of Ohio, have invented an Improvement in Cuff or Sleeve Buttons, of which the following is a specification.

My invention relates to improvements in an adjustable cuff or sleeve button; and the object of my improvement is to provide an adjustable cuff or sleeve button by which the cuff or sleeve may be readily and quickly fastened without tearing or defacing the cuff or button-hole, and which is both cheap and durable. I attain these objects by the combinations and mechanism hereinafter fully described, and illustrated in the accompanying drawings, in which—

Figure 1 is a bottom view of my device; Fig. 2, a sectional view taken on the line *x x* of Fig. 1. Figs. 3, 4, and 5 are top views with the cover removed, showing in detail the several parts hereinafter more fully described.

Similar letters refer to similar parts throughout the several views.

A represents a metallic casing of any ornamental design, containing the mechanism for operating the device, and is made square, having top, bottom, and sides. On the center of the bottom of casing *A*, on the outside thereof, projects a shank, *a*.

Extending from the outside end of shank *a*, up through it nearly to the top of the casing *A*, is a pivot or loose rod, *D*, bent at right angles at its upper end, forming an arm, *d*, about one-half the width of the casing *A*, and on the lower end of pivot *D*, and immediately below the shank *a* and independent thereof, is rigidly secured the catch *B*.

On the inside of the casing *A*, in the center and suspended on or encircling the pivot *D*, is a metallic drum, *C*, made similar in shape to a capstan, the lower end being cut away, as shown at *c c* in Fig. 2, and at its upper end

having a circular face, *E*, with one section or quarter of the circle removed. The arm *d* of pivot *D* projects in such a manner that when the drum *C* is revolved the broken segment of the circular face *E* will strike and remove it.

On the inside of the casing *A* are small pins

or projections *e e*, as shown in Figs. 3 and 4, against which the arm *d* strikes, limiting the distance of its movement.

On the inside of the bottom of the casing *A*, extending diagonally across and secured at its ends, is a leaf-spring, *S*, which rests against the bottom of the drum *C* and holds it firmly in position when not being moved. Secured to the drum *C* by both its ends is a small chain, *F*, which passes through holes *o o* in one side of the casing *A*, and hangs on the outside in the form of a loop, ready for operation and as an ornament.

My sleeve-button, thus constructed, can be made of any material desired, and ornamented in any manner.

The manner of operation is as follows: To fasten the button in the cuff, pass the shank *a*, with the head or catch *B* on a line with shank *a*, through the button-hole, pull the side of the chain *F* nearest the hand, which will turn the drum *C*, and the edge of the circular face *E* will strike against the pivot-arm *d*, moving it until it is stopped by the projection or pin *e*. This movement will turn the pivot *D*, which carries with it the catch *B*, so that *B* will be at right angles to shank *a*, and the cuff will be fastened, and the several parts will be held firmly in position by the pressure of the leaf-spring *S*. To unfasten the cuff the other side of the chain is pulled, which reverses the action, and the catch is brought back to its normal position, and may then be easily removed from the cuff.

Having thus described my invention, what I claim as new, and desire to secure by Letters Patent, is—

1. The combination, in a cuff-button, of the casing *A*, provided with shank *a* and holes *o o* and pins *e e*, with the pivot *D*, having right-angled arm *d* and catch *B*, substantially as shown and described, and for the purpose set forth.

2. In a cuff-button, the combination of casing *A*, provided with holes *o o*, shank *a*, and pins *e e*, the pivot *D*, having arm *d*, catch *B*, the drum *C*, having segmental face *E*, spring *S*, and chain *F*, all arranged and operating substantially as described and shown.

3. The combination, in a cuff-button, of a

casing having a shank attached thereto, a pivot-pin extending through said shank and into the casing, a shoe or catch secured to the end of the pivot-pin and adapted to rotate in contact with the end of the shank, a drum surrounding the inner end of the pivot-pin, a spring for holding said drum in position, and means for rotating the drum and pivot for the purpose of turning the shoe or catch into a

position parallel with or at right angles to the shank, substantially as described.

In testimony whereof I affix my signature in presence of two witnesses.

WARD W. YOUNG.

Witnesses:
